UNITED STATES PATENT OFFICE.

CHARLES B. GIBSON, OF CHICAGO, ILLINOIS.

DESIGN FOR A NON-SKID PLATE FOR AUTOMOBILES.

57,898.

Specification for Design.

Patented May 17, 1921.

Application filed October 16, 1919. Serial No. 331,211. Term of patent 7 years.

To all whom it may concern:

Be it known that I, CHARLES B. GIBSON, a citizen of the United States, residing at Chicago, county of Cook, and State of Illinois, have invented a new, original, and ornamental Design for Non-Skid Plates for Automobiles, of which the following is a specification, reference being had to the accompanying drawings, forming a part thereof.

Figure 1 is a face view of a non-skid plate showing my new design; and

Fig. 2 is a sectional view of the same on line 2—2 of Fig. 1.

I claim:

The ornamental design for a non-skid plate for automobile tires substantially as shown.

CHARLES B. GIBSON.
